COACH BODY FOR CAMPING OR THE LIKE

Donald F. Sloat, 111 W. Lowden, Fort Worth, Tex.

Filed Nov. 16, 1961, Ser. No. 67,557

Term of patent 7 years

(Cl. D14—3)

Fig. 1

Fig. 2

FIG. 1 is a rear perspective view of a coach body for camping or the like showing my new design; and

FIG. 2 is a front perspective view thereof.

The side not shown is a mirror image of the side shown. The automobile shown in broken lines in FIG. 1 is included for illustrative purposes only.

I claim:

The ornamental design for a coach body for camping or the like, as shown and described.
